THE COLUMBIA PLANOGRAPH CO., WASHINGTON, D. C.

UNITED STATES PATENT OFFICE.

SAMUEL WILEY, JR., OF METUCHEN, NEW JERSEY.

TIME-FUSE FOR AERO-BOMBS.

1,319,635.

Specification of Letters Patent. Patented Oct. 21, 1919.

Application filed March 21, 1919. Serial No. 283,985.

To all whom it may concern:

Be it known that I, SAMUEL WILEY, Jr., a citizen of the United States, residing at Metuchen, in the county of Middlesex and State of New Jersey, have invented certain new and useful Improvements in Time-Fuses for Aero-Bombs; and I do hereby declare the following to be a full, clear, and exact description of the invention, such as will enable others skilled in the art to which it appertains to make and use the same.

My invention relates to improvements in time fuses for bombs adapted to be dropped from aircraft.

15 The invention is intended to provide a safe and reliable device by means of which such bombs may be exploded at the desired predetermined instant after being released from the aircraft, and in which any premature or accidental explosion, due to the failure of the parts to operate properly, is impossible.

20 My invention will be more clearly understood after reference to the accompanying drawings, in which like parts are indicated by similar reference symbols throughout the several views, and in which:—

Figure 1 is a front view of the fuse and the handle attachment for the bomb as removed from the bomb, parts being broken away.

Fig. 2 is a side view of the device shown in Fig. 1, as seen from the left of said figure.

Fig. 3 shows a section along the line 3—3 of Fig. 1 and looking down.

Fig. 4 shows a section along the broken line 4—4 of Fig. 3 and looking in the direction of the arrows, but with the hammer cocked.

40 Fig. 5 shows a section along the line 5—6 of Fig. 4 and looking in the direction of the arrows, the fuse being shown in the safety position.

Fig. 6 is a similar view to Fig. 5 which shows the fuse in the armed position.

Fig. 7 shows a section along the line 7—7 of Fig. 6 and looking in the direction of the arrows, the parts being shown on a larger scale.

50 Fig. 8 is a perspective view of the hammer for firing the cap.

Fig. 9 is a perspective view of the fuse stock carrying the time train.

Fig. 10 is a perspective view showing the rotary cap in the inverted position.

Fig. 11 is a perspective view of the cross

head mounted above the cap and to which the handle is connected.

Fig. 12 is a perspective view of the trigger showing the underside thereof.

Fig. 13 is a perspective view showing in inverted position the housing mounted above the heel of the trigger, and

Fig. 14 is a perspective view of the handle as detached from the fuse after the bomb has been released therefrom.

A represents the fuse stock which is in the form of a hollow cylinder chambered as at A° to receive the rotary cap B.

C represents the hammer actuated by the spring C'.

D represents the cross head to which the handle is attached.

E represents the trigger, and F represents the trigger housing mounted on the cross head.

G represents the securing screw connecting the fuse stock, the rotary cap and cross head together.

H represents the handle, I the spring impressed plunger for holding the cross head against turning on the rotary cap, and K represents the safety pin.

Referring to the parts more specifically, the fuse stock A is in the form of a cylindrical cup chambered as at A° and screw-threaded exteriorly as at a to engage screw threads in the head of the bomb. The bomb is not shown, as the invention relates primarily to the time fuse and is adapted for use with a great variety of bombs.

The fuse stock is flanged as at a', and this flange is provided with a safety notch a" and with time notches a", whose function will be hereinafter described.

95 The upper inner edge of the fuse stock is chambered as at a° to receive the time train M, which preferably consists in a slow burning train of powder inclosed in a fusible tube of lead or an inflammable tube, which is melted or ignited when the primer is exploded, as will be hereinafter described.

Projecting up into the center of the chamber A° is the spindle A' which may be integral with, or attached to the fuse stock A, as by means of the locking pin a", see Fig. 4. In any event this spindle A' is to all intents and purposes an integral part of the fuse stock A.

105 Mounted in this fuse stock is the rotary cap B having a cylindrical shell b inclosing

the chamber B^o , which shell projects down into the chamber A^o of the fuse stock A. This rotary cap is shown in the proper position in Fig. 4, but in the inverted position 5 in Fig. 10. This cap is provided with a flange b' adapted to register with the upper face of the flange a' of the fuse stock, and this flange is provided with a notch b^2 to assist in setting the fuse at the proper time 10 interval, which will be hereinafter described.

Projecting down into the chamber B^o of the rotary cap is a lug B' having a plane face b^3 from which projects the primer n which ignites the charge of powder N held 15 in a chamber in the lug B' , as shown in Figs. 4, 5, 6 and 10. The shell b is preferably cut away as at b^4 for convenience in putting the primer n in place.

C represents the hammer which is provided with a striking arm c adapted to strike the primer n , and is cut away as at 20 c' to permit the insertion of the firing spring C' which is preferably in the form of a coil spring slipped over the spindle A' and having one end engaging an abutment in the rotary cap, and the other end engaging the hammer arm c , as shown in Figs. 4, 5 and 6. This hammer also slips over the spindle A' and is notched as at c^2 to engage the lugs 25 e^2 on the heel of the trigger E. This heel of the trigger is perforated, as at e' , to slip over the spindle A' and has an arm e adapted to engage an abutment on the handle, which will be hereinafter described.

D represents a cross head centrally perforated as at d^o to slip over the spindle A', and having downwardly projecting arms d adapted to slip over the outer edge of the flange a' of the fuse stock. This cross head 30 is provided with a catch d' adapted to engage in any one of the notches in the flange of the fuse stock and also with a resilient friction arm d^2 adapted to bind against the outer face of said flange and steady the cross head while it is being moved or while it is 35 in the unlocked position. This spring serves as a friction brake to prevent too quick rotation of the rotary cap C in setting the fuse.

The cross head is also provided with a socket d^3 for the spring plunger I which is normally pressed downward by the spring I' into engagement with a notch b^5 in the rotary cap B, as shown in Figs. 1 and 4, so as 40 to cause the cap and the cross head to rotate together when desired. This plunger and spring are held in place by the milled screw head i , see Figs. 1 and 4. The cross head D is provided with a groove d^5 at each end 45 thereof, into which grooves project the pins d^4 adapted to engage the handle as will be hereinafter described.

F represents the housing block for the trigger, which is provided with a lug f perforated as at f^o to receive the securing

screw G, and is recessed as at f' to engage the outer edge of the heel of the trigger. This housing is provided with suitable pins or lugs f^2 adapted to engage in the sockets d^6 in the cross head D, see Figs. 4, 11 70 and 13.

The detachable handle is shown in Figs. 1 to 4 and 14, and preferably consists of two members H' and H^2 pivoted together, as will now be described. The inner member 75 H' is preferably in the form of a rectangular loop with lower forked ends h , slotted as at h^o , and preferably bent inward slightly as at h' , so as to provide suitable yielding frictional engagement.

One side of this loop H' is provided with a rib h^2 which serves as a stop to prevent the handle from being pressed down too far, and there is a similar stop h^3 which serves also to engage the trigger arm e , as will be 80 85 hereinafter described.

Secured to the sides of the loop H' are the screws h^4 which project into the slots h^5 in the sides of the outer loop H^2 of the handle, shown in Fig. 14, and this outer loop 90 has downwardly projecting legs provided with hooks h^6 and with guide faces h^7 above said hooks. The sides of the loops H' and H^2 are perforated as at h^8 and h^9 so that when the handle is secured on the fuse the 95 safety pin K may be inserted, as shown in Fig. 1, thus effectually locking the handle in the safety position, and the handle cannot be "broken" or swung to the releasing position so long as this safety pin is in 100 place.

The outer loop H^2 of the handle is pressed away from the inner loop by means of a spring H^3 .

The operation of the device is as fol- 105 lows:—

Supposing the parts to be assembled in the safety position, first turn the handle until the pin I on the crosshead D engages in the socket b^5 on the top of the cap, thus locking 110 the crosshead and cap together and cocking the hammer. In this position the fuse will be set to burn about five seconds. If a longer time is wanted, continue to turn the handle and cap B to the time desired. If 115 for any reason the fuse or bomb is not used when thus set, it may be turned back to the safety position with the hammer cocked.

The lug h^3 on the handle will engage the trigger arm e , and incident to this operation 120 the powder mass N has been moved from registering with the abutting wall a^6 of the fuse stock to a position opposite the time train M, the rotary cap being turned from the position shown in Fig. 5 to that shown 125 in Fig. 6. The hammer is prevented from yielding to the action of the hammer spring C' because of the engagement of the trigger arm e with the stop h^3 on the handle, as shown in Figs. 1 and 3. Thus so long as the 130

handle is attached to the fuse, the hammer is held in the cocked position and cannot be released or cannot move to the firing position.

5 At this time the handle will be firmly locked to the fuse and incidentally to the bomb, and the safety pin K being in place the handle cannot be removed from the device, so that the parts are in the absolutely safety position; but the fuse is armed and set at the proper time interval.

Now if it is desired to drop the bomb with the fuse so set, lift the bomb by the handle and hold it in the proper position for dropping, remove the safety pin K and press the outer loop H^2 downward against the action of the spring H^3 . This may be accomplished by simply squeezing the loops H' and H^2 together by a single grip of the hand. The downward movement of the loop H^2 relative to the loop H' will cause the cam faces h^7 to engage the pins d^4 and will throw the hooks h^6 out of engagement, thus leaving the handle attached only to the mechanism by the frictional engagement of the arms h . The weight of the bomb will be more than sufficient to overcome this frictional engagement, and the bomb and the parts carried thereby will drop clear of the handle, leaving the handle in the hand of the operator.

Soon after the bomb begins to drop downward clear of the handle, the trigger arm e will pass clear of the stop h^8 on the handle, leaving the hammer spring free to rotate the hammer to the firing position, causing it to strike the primer n and to ignite the powder charge N . The heat and pressure of this powder charge will be sufficient to melt or break the wall of the powder train M and this time train will burn for the predetermined time before it reaches the point m , where it ignites the ignition charge M' , see Fig. 7.

This ignition charge M' ignites the explosive charge in the bomb not shown. The lower end of the recess inclosing this ignition charge M' may be closed in any convenient way, as by means of a thin strip m' . Thus it will be seen that when the fuse is set at the predetermined time interval when the projectile is dropped clear of the handle, the time train will be ignited and the fuse will function properly for the time interval for which it is set.

55 To prevent against accident from premature explosion in case the operator, through inadvertence or carelessness, fails to set the fuse at the desired time interval I construct the fuse so that the charge N ignited by the primer n will blow out without exploding the bomb when the bomb is released with the parts in the safety position. To accomplish this result the groove a^3 in the fuse stock containing the time train M is inter-

rupted, and the plane cylindrical wall a^6 65 is provided, as shown in Fig. 5.

When the fuse is not set for any time interval, and the parts are in the safety position shown in Fig. 5, the powder charge N will register with this wall a^6 , and if the 70 hammer is operated, the gases from the powder charge N will escape through the opening b^6 , see Figs. 3 and 4.

Thus, even if the hammer should strike the primer when the fuse is not set at an 75 adequate time interval, there will be a simple blow-out of the primer charge without setting the time train; whereas if the fuse is set at an appreciable time interval the bomb will drop far enough away from the 80 handle when released before it explodes, so that the operator will be perfectly safe from premature explosion.

I do not mean to confine the invention to any particular form of bomb releasing device or primer igniting device, as these obviously might be varied in many ways without departing from the spirit of my invention.

It will be obvious also that various other 90 modifications might be made in the construction, combination and arrangement of parts which could be used without departing from the spirit of my invention; and I do not mean to limit the invention to such details except as particularly pointed out in the claims.

Having thus described my invention what I claim and desire to secure by Letters Patent of the United States is:—

1. A time fuse for aero bombs comprising a fuse stock adapted to be attached to the bomb, and provided with a time train, a rotary cap mounted in said fuse stock, and provided with a primer adapted to ignite 105 said time train, a spring impressed hammer normally tending to strike said primer, a trigger controlling said hammer, and a handle attached to said fuse for supporting the bomb, and normally holding said trigger 110 in the cocked position, but releasing said trigger when the handle is detached, substantially as described.

2. A time fuse for aero bombs comprising a fuse stock adapted to be attached to the bomb, and provided with a time train, a rotary cap mounted in said fuse stock and provided with a primer adapted to ignite 115 said time train, a spring impressed hammer normally tending to strike said primer, a trigger controlling said hammer, a handle for supporting the bomb carried by said fuse, and means carried by said handle for holding said trigger in the cocked position, and releasing same when desired, substantially as described.

3. A time fuse for aero bombs comprising a fuse stock adapted to be attached to

- the bomb, and provided with a time train, a rotary cap mounted in said fuse stock, and provided with a primer adapted to ignite said time train, means for setting said rotary cap at any desired position relative to said time train, a spring impressed hammer carried by said rotary cap and normally tending to strike said primer, a trigger controlling said hammer, and a handle attached 5 to said fuse for supporting the bomb, and normally holding said trigger in the cocked position, but releasing said trigger when the handle is detached, substantially as described. 10
- 15 4. A time fuse for aero bombs comprising a fuse stock adapted to be attached to the bomb, and provided with a time train, a rotary cap mounted in said fuse stock, and provided with a primer adapted to ignite 20 said time train, means for setting said rotary cap at any desired position relative to said time train, a spring impressed hammer carried by said rotary cap and normally tending to strike said primer, a trigger controlling said hammer, a handle for supporting the bomb carried by said fuse, and means for holding said trigger in the cocked position, and releasing same when desired, substantially as described. 25
- 30 5. A time fuse for aero bombs comprising a fuse stock adapted to be attached to the bomb, and provided with a time train, a rotary cap mounted in said fuse stock, and provided with a primer adapted to ignite 35 said time train, a spring impressed hammer normally tending to strike said primer, a trigger controlling said hammer, a handle detachably connected to said fuse for supporting the bomb, and normally holding said 40 trigger in the cocked position, but releasing said trigger when the handle is detached, and means for quickly releasing said handle from said fuse when desired, and thus releasing the bomb. 45
- 50 6. A time fuse for aero bombs comprising a fuse stock adapted to be attached to the bomb, and provided with a time train, a rotary cap mounted in said fuse stock, and provided with a primer adapted to ignite 55 said time train, means for setting said rotary cap at any desired position relative to said time train, a spring impressed hammer carried by said rotary cap and normally tending to strike said primer, a trigger controlling said hammer, a handle detachably connected to said fuse for supporting the bomb, and normally holding said trigger in the cocked position, but releasing said trigger when the handle is detached, and means for 60 quickly releasing said handle from said fuse when desired, and thus releasing the bomb. 65
7. A time fuse for aero bombs comprising a fuse stock adapted to be attached to the bomb, and provided with a seg- 65 mental groove and a time train mounted
- therein, a rotary cap mounted in said fuse stock, and provided with a primer adapted to ignite said time train but to be inoperative when registering with the space between the ends of the time train, a 70 spring impressed hammer normally tending to strike said primer, a trigger controlling said hammer, a handle for supporting the bomb carried by said fuse, and means for holding said trigger in the cocked position, and releasing same when desired, substantially as described. 75
8. A time fuse for aero bombs comprising a fuse stock adapted to be attached to the bomb, and provided with a segmental groove 80 and a time train mounted therein, a rotary cap mounted in said fuse stock, and provided with a primer adapted to ignite said time train, but to be inoperative when registering with the space between the ends of said 85 time train, means for setting said rotary cap at any desired position relative to said time train, a spring impressed hammer carried by said rotary cap and normally tending to strike said primer, a trigger controlling said 90 hammer, a handle for supporting the bomb carried by said fuse, and means for holding said trigger in the cocked position, and releasing same when desired, substantially as described. 95
9. A time fuse for aero bombs comprising a fuse stock adapted to be attached to the bomb, and provided with a time train, a spindle projecting upwardly into said stock, a rotary cap mounted in said fuse stock and journaled on said spindle, and provided with a primer adapted to ignite said time train, a spring impressed hammer also journaled on said spindle and normally tending to strike said primer, a trigger also journaled 100 in said spindle and controlling said hammer, and a handle attached to said fuse for supporting the bomb, and normally holding said trigger in the cocked position, but releasing said trigger when the handle is detached, 105 substantially as described. 110
10. A time fuse for aero bombs comprising a fuse stock adapted to be attached to the bomb, and provided with a time train, a spindle projecting upwardly into said stock, a 115 rotary cap mounted in said fuse stock and journaled on said spindle, and provided with a primer adapted to ignite said time train, a spring pressed hammer also journaled on said spindle and normally tending to strike said primer, a trigger also journaled in said spindle and controlling said hammer, and means for holding said trigger in the cocked position, and releasing same when desired, 120 substantially as described. 125
11. A time fuse for aero bombs comprising a fuse stock adapted to be attached to the bomb, and provided with a time train, a spindle projecting upwardly into said stock, a rotary cap mounted in said fuse 130

- 6
- provided with a primer adapted to ignite said time train, means for setting said rotary cap at any desired position relative to said time train, a spring impressed hammer, normally tending to strike said primer, carried by said rotary cap, a trigger also journaled on said spindle and controlling said hammer, a handle detachably connected to said fuse for supporting the bomb, and normally holding said trigger in the cocked position, but releasing said trigger when the handle is detached, and means for quickly releasing said handle from said fuse when desired, and thus releasing the bomb.
- 15 19. A time fuse for aero bombs comprising a fuse stock adapted to be attached to the bomb, and provided with a segmental groove and a time train mounted therein, a rotary cap mounted in said fuse stock, and provided with a primer adapted to ignite said time train, but to be inoperative when registering with the space between the ends of said time train, means for setting said rotary cap at any desired position relative to said time train, a spring impressed hammer carried by said rotary cap and normally tending to strike said primer, a trigger controlling said hammer, and means for holding said trigger in the cocked position, and releasing same when desired, substantially as described.
- 20 20. A time fuse for aero bombs comprising a fuse stock adapted to be attached to the bomb, and provided with a segmental groove and a time train mounted therein, a rotary cap mounted in said fuse stock, and provided with a primer adapted to ignite said time train, but to be inoperative when registering with the space between the ends of said time train, means for setting said rotary cap at any desired position relative to said time train, a spring impressed hammer carried by said rotary cap and normally tending to strike said primer, a trigger controlling said hammer, and means for holding said trigger in the cocked position, and releasing same when desired, substantially as described.
- 25 21. A time fuse for aero bombs comprising a fuse stock adapted to be attached to the bomb, and provided with a segmental groove and a time train mounted therein, a rotary cap mounted in said fuse stock, and provided with a primer adapted to ignite said time train, but to be inoperative when registering with the space between the ends of said time train, means for setting said rotary cap at any desired position relative to said time train, a spring impressed hammer carried by said rotary cap and normally tending to strike said primer, a trigger controlling said hammer, and means for holding said trigger in the cocked position, and releasing same when desired, substantially as described.
